COLOR HARMONY SELECTION ASSEMBLY

Edith Jean Blanc Miller, Chicago, Ill., assignor to Desarco Corporation, Chicago, Ill., a corporation of Illinois

Filed Jan. 4, 1954, Ser. No. 402,095

3 Claims. (Cl. 35—28.3)

The instant invention relates to a color harmony selection system by means of which a user can rapidly and conveniently select harmonious color combinations from an extremely wide variety of selections.

Previously used color harmony selection systems have not always met with approval by decorators and other artists interested in the problem of color design. In some of the systems previously employed, the number of possible color combinations derivable from the system has been rather limited. In other systems which permit a wider selection of color combinations from which to choose appropriate color harmonies, the systems employed are sometimes unwieldy and require the services of an expert trained in color theory for operation. Such systems are, of course, impractical commercially because they are beyond the prowess of the ordinary layman who might be interested in selecting a harmonious color arrangement for rooms in his own home.

The present invention provides a color harmony selection system which overcomes the disadvantages associated with the previous color harmony selection systems. The system of my invention is capable of presenting different color combinations which number in the millions. Yet at the same time the system is sufficiently flexible and sufficiently uncomplicated that it may be employed to advantage by those unskilled in color selection or the theory of colors.

This is a continuation-in-part of my copending application Serial No. 235,327, filed July 5, 1951, now Patent No. 2,665,503, in which the claims emphasize the concept of employing certain positional arrangements for color indicia that are tints or shades of a given color. The instant invention relates to the arrangement of color indicia on one or more arrays so as to obtain improved interchangeability between arrays and an improved number of cooperating positions for such arrays, so as to function adequately with a mask that is uniquely adapted for cooperation therewith.

It is, therefore, an important object of the instant invention to provide an improved color harmony selection system which permits the selection of harmonious color combinations among a very wide variety of choices.

A further object of the present invention is to provide a color harmony selection system which can be manipulated and used effectively by persons relatively unskilled in the theory and practice of decorating.

Another object of the instant invention is to provide a color harmony selection system consisting of only a few basic components, which are uniquely capable of being interchanged in positional relationship.

Another object of the present invention is to provide a color harmony selection system which is unique in that any one, two, or more arrays may be used together at any one time, so that the color user can make his own choice of the particular color arrays, as the red array, and the green array, or the blue green array, etc. which he will use together and from which he will make his

2

final selection of color indicia for a scheme, according to his own needs.

Another important object of the present invention is to provide a novel type of color array for use in color harmony selection systems.

Still a further object of the instant invention is to provide an improved mask for use in a color harmony selection system.

Another important object of the present invention is to provide a new selection system whereby one may select schemes which vary from each other in the number of individual color members involved so that a user may find a scheme with few colors or one with many colors, as his particular purpose demands.

Another very important object of the instant invention is to provide a unique device for presenting great numbers of color schemes in each of which the same color sample can appear, so that a color user is enabled to build any one of a number of color harmonies around

some item of predetermined color which he already has, and so that a student of color may study the relativity of color by observing the varying effects produced when the same color sample is viewed in various combinations with other color samples and to see how the same color sample may appear lighter or darker or more vivid or less vivid as it is seen in combination with other colors.

Another equally important object of the present invention is to provide a unique selection system which will present many types of color schemes, schemes varying from each other in their degrees of contrast of light and dark colors or of vivid and dull colors, so that the color user may find a scheme of the precise degrees of color contrast for his particular purpose.

Another object of the instant invention is to provide an improved neutral scale which may be used when desired, and which is uniquely capable of being variously repositioned in reference to the color arrays without any of its edges obscuring the individual color indicia which are located on the color array in a row next to the neutral scale edge.

Still a further object of the present invention is to provide a selection system which can be used as a teaching device, or a game, in which the interchangeable and variously repositionable arrays will exhibit individual colors,

letters, or words, or numbers, or other symbols and in which a mask will act as a selector of meaningful combinations of colors, or letters, or words, or numbers, or other symbols.

Other and further objects, features and advantages of the instant invention will become apparent to those skilled in the art from the following detailed disclosure thereof and from the attached sheets of drawings which form a part thereof.

In the drawings:

55 Figure 1 is a plan view of a color selection system embodying the instant invention, including a mounting board, color arrays and a neutral scale disposed thereon, with a mask superimposed upon the arrays neutral scale and mounting board;

60 Figure 2 is a plan view of the color selection system shown in Figure 1, with the mask removed;

Figure 3 is a plan view of a second array arrangement embodying the instant invention and using the arrays shown in Figures 1 and 2;

65 Figure 4 is a plan view of a third array arrangement embodying the instant invention;

Figure 5 is a plan view of a fourth array arrangement embodying the instant invention;

Figure 6 is an array arrangement showing a fifth embodiment of the instant invention;

Figure 7 is a fragmentary detail view showing the man-

3

ner in which one of the colored members or indicia may be detachably secured to an arry used in the instant invention;

Figure 8 is a detail view of an array which may be used in the practice of the instant invention, particularly as a neutral scale;

Figure 9 shows a sixth array arrangement embodying the instant invention;

Figure 10 is a plan view of a seventh array arrangement embodying the instant invention;

Figure 11 is a plan view of an eighth array arrangement embodying the instant invention;

Figure 12 is an array arrangement shown in plan view embodying a ninth arrangement of the invention;

Figure 13 shows in plan view a tenth array arrangement embodying the instant invention;

Figure 14 shows in plan view an eleventh array arrangement embodying the instant invention;

Figure 15 shows in plan view a twelfth array arrangement embodying the instant invention;

Figure 16 shows in plan view a mounting board and array arrangement that constitutes a thirteenth embodiment of the instant invention; and

Figure 17 is a view in elevation of the mounting board of Figure 16.

As shown in the drawings:

As indicated in Figures 1 and 2, the selection system of the present invention may include a laminated flat locking board 10 which may be suitably composed of relatively stiff material such as heavy cardboard and the like. The interior of the mounting board 10 is recessed, as indicated generally by the numeral 11, leaving the upstanding marginal edges 12, 13, 14 and 15 about the recessed interior of the mounting board 10.

It should be pointed out at this time that the mounting board 10 provides an additional convenience for operating the instant device in that it assists in retaining the various arrays in the positions desired; but such arrays may also be retained on any suitable mounting means, such as a table, by means of thumb tacks or some other fastening device. The instant mounting board 10 is particularly advantageous in that it effectively retains the arrays in position while at the same time permitting ready substitution of one array for another in a given position.

One of the significant features of the present invention resides in the type of color array used in conjunction with the instant color harmony selection system. As described in detail in my copending application Serial No. 235,327, which disclosure is made a part hereof by reference for the purpose of supplementing the instant disclosure, it is preferable to employ one color array for each of the basic colors. The selection of two or more basic colors which may be used is described in detail in said application Serial No. 235,327 with respect to the operation of the color wheel shown in Figure 1 thereof, and need not be further discussed herein. It will be appreciated, however, that one of the particular advantages of the invention described and claimed herein is that it provides for the maximum number of color combinations and in this respect it would not be absolutely necessary to employ color indicia on a given array which are all tints or shades of a given pure color. For the systematic use of the instant device and so as to take maximum advantage of the great number of color combinations attainable using this device, each color array is provided with color indicia for only one of said basic colors.

Referring to Figure 2 again, it will be noted that each of the six color arrays, indicated by the reference numerals 16, 17, 18, 19, 20, 21 and 22 consists of a polygonal-shaped member, in this case shown as a generally triangularly-shaped member, preferably made of white material and having a plurality of color particles or indicia detachably secured thereto.

As shown in Figure 7, the individual color particle 23

4

is preferably in the shape of a rhombus so that the opposite ends 23a and 23b of the particle 23 may be slipped underneath a portion of the array, indicated fragmentarily at 24, through a slit opening at 24a and 24b respectively, thereby leaving the exposed portion of the color particle 23 in the form of a hexagon. It will be appreciated that the instant invention does not preclude the use of other types of color indicia or the use of different detachable fastening means; but the arrangement here shown has been found to be particularly satisfactory. In referring subsequently to alignment of the color indicia or particles, such alignment has reference to the center or approximate center of the exposed portion of the color particle, which would be at C in Figure 7.

Referring now to Figure 2 again, it will be noted that the device 10 comprises a pair of color arrays 16 and 17 disposed with an edge 16a of the array 16 parallel to an edge 17a of the array 17, each of the arrays 16 and 17 having individual color indicia affixed thereto, the indicia 20 a, b, c and d plus the indicia f, g, h and i being aligned in a first set of parallel rows (the row a, b, c, d being parallel with the row f, g, h, i) and the indicia j, b, k and l plus the indicia m, c, h and n being aligned in a second set of parallel rows (namely the row j, b, k, l being 25 parallel to the row m, c, h, n). The first set of parallel rows which includes the rows a, b, c, d and f, g, h, i is intersected by the second set of parallel rows which includes the rows j, b, k, l and m, c, h, n, in each case at the centers of the indicia. For example, the row a, b, 30 c, d intersects the row j, b, k, l at the center of the color particle b, etc. At least one of such sets of parallel rows is aligned so as to intersect the parallel edges 16a and 17a, and preferably both sets of rows are so aligned, as shown in Figure 2.

Also, it will be noted that the indicia in each row of said sets of rows are spaced an integer multiple of a predetermined unit of distance "x" from any indicia in that row immediately adjacent thereto. This may be clarified by reference to the row p, o, l, n, q, r, s, . . . t (which 40 is here referred to for the purpose of convenient location of the dimension notations in Figure 2); it will be seen that the distance between each of the color indicia in this row is the predetermined unit "x." The color indicia b, c and d in the array 16 are likewise spaced the distance "x" apart, but the indicia a and b in this same row a, b, c, d are spaced apart the distance 2x. In like manner, the indicia m, c and h in the array 16 are spaced from each other the distance x, whereas the indicia h and n are spaced apart the distance 2x in the row m, c, h and n. It will thus be seen that the pattern here presented by the indicia is that wherein the indicia on both arrays 45 16 and 17 are aligned in two different sets of parallel rows which intersect and the indicia in each row of these sets of rows are spaced an integer multiple of a predetermined unit of distance x from the immediately adjacent indicia. In a given array, such as the array 16, each of the indicia in any particular row of indicia is preferably spaced from the others immediately adjacent by the distance x instead of an integer multiple of x. By "integer multiple" is meant a whole number multiple, such as 1x, 2x, 3x, etc. It will be appreciated that, even though "color" is used herein for purposes of example, any intelligence conveying indicia can be used such as letters, words, numbers, etc. for use in a game, for example; and such indicia including the color indicia may be mounted detachably or otherwise, such as by printing.

It will be seen that the relationship between any two of the other arrays shown in Figure 2 which are adjacent is the same as that described in connection with the arrays 50 16 and 17. It will also be seen that in this preferred embodiment of the invention shown in Figures 1 and 2, the indicia on any one of the arrays are spaced in their respective rows by the predetermined unit of distance x, whereas the indicia, such as the indicia a and b which are immediately adjacent each of parallel edges

16a and **17a** are aligned in one of the rows, *a*, *b*, *c*, *d* are spaced from each other an integer multiple (preferably two) of a predetermined unit of distance *x*. The spacing of the arrays **16** and **17** in this manner results in an increased number of color combination possibilities for certain purposes by virtue of the blank space provided between the edges **16a** and **17a**. As will be explained hereinafter, the mask **25** (Figure 1) has a number of indicia-sized windows (i.e. adopted to expose a part or all of a single indicium) therein that are so positioned that they may be readily aligned with various indicia, but it is often advantageous to have a blank space on the mounting board **10**, such as that provided between the parallel edges **16a** and **17a** which permits one of the windows to act as a closed window, even though it is centrally located. This will be explained hereinafter in more detail.

Referring again to Figure 2, it will be noted also that the center portion of the mounting board **10** contains a hexagonal array **26**. This hexagonal array **26** has a total of 6 color indicia (which includes *q* and *r*) thereon and these color indicia are preferably made up to comprise the so called neutral scale, which includes black and white and various shades of gray which are increasingly more shaded from light gray to dark gray. The concept of employing a neutral scale is described in detail in said copending application Serial No. 235,327 and need not be further described herein. The important feature in connection with the instant neutral scale array **26** is that that indicia therein are also alignable in two intersecting sets of parallel rows, as is obvious from observing the drawing. In addition, the indicia on the neutral scale array **26** are spaced from each other in any one of said rows by the predetermined distance unit *x*, as indicated in connection with the indicia *q* and *r*. In this manner, the indicia on the neutral scale array **26** are also alignable in the sets of parallel rows hereinbefore indicated in connection with the adjacent arrays **16**, **17**, etc. In this manner, the entire pattern for the indicia on the mounting board **10** is set.

By the use of the instant arrangement pattern for the indicia on the mounting board **10**, it is possible to employ a mask having windows positioned therein in a related positional relationship so as to greatly increase the possible color combinations which may be obtained.

Referring now to Figure 1, it will be seen that the arrangement set forth in Figure 1 includes the mounting board **10**, the neutral scale array **26** and a total of 3 color arrays **16**, **17** and **21**. (The dotted line reference to the edges of the recessed center of the board **10**, indicated by the reference numeral **11**, have been omitted from Figure 1 for the sake of simplification.) In Figure 1, the color harmony selection is to be made between the neutral scale and certain colored arrays, which are the arrays **16**, **17** and **21** representing three different colors. If it is desired to make a selection among more colors, then more arrays may be suitably positioned on the board **10**, and if it is desired to make a selection between only two colors, for example, the array **21** may be removed.

The windows **27** through **40** indicated on the mask **25** are positioned to some extent in a random manner, although the positioning of these windows is based upon the same pattern theory for arranging the color indicia. In other words, the windows are positioned in at least two sets of parallel rows, one set being indicated by parallel lines drawn through the window row **27**, **28**; the row **30**, **31**; the row **32**, **33**; the row **34**, **35**; and the row **38**, **39**, **40**. Another set of rows of parallel alignment is defined by the row **33**, **36**, **40**; the row **31**, **37**; the row **28**, **32**, **39**; etc. Still a third set of parallel rows would be indicated by the windows in the row **27**, **31**; the row **29**, **32**; the row **30**, **35**, **37**; etc. As will be explained hereinafter, the most preferred indicia arrange-

ment calls for 3 (not 2) sets of parallel intersecting rows and this arrangement is also preferred in the case of the windows in the mask **25**. It will also be noted in the mask **25** that the spacing between adjacent windows in any given row is an integer multiple of the predetermined unit of distance *x*. This dimensional arrangement is shown in Figure 1 in connection with the row **38**, **39**, **40**; the row **35**, **37**; and the row **27**, **28**. By using the instant positional relationships between the color indicia and the windows, it is possible to obtain a maximum number of color combinations by relatively simple manipulation of the mask **25**. The first step being to align the windows in any given row on the mask **25** with a line that is parallel to or the same as a line drawn through a row of color indicia in one of said sets of parallel rows. Then, as soon as one window is centered on one color indicia, the other windows which are over color indicia will also be centered with respect thereto. Thus, in the view shown in Figure 1, the window **32** is centered on the color indicia *q* in the neutral scale array **26** and the window row **32**, **33** is aligned with the indicia row *p*, *o*, *l*, *n*, *q*, *r*. This results in the centering of the window **36** over the color particle *u* in the array **21**, the centering of the window **30** over the color particle *w* in the array **17** and the centering of the windows **27** and **28** over the color particles *j* and *z*, respectively, in the array **16**. It will also be noted that the window **29** is positioned over the space between the parallel edges **16a** and **17a** so that this window functions as a closed window in this particular position. The remaining windows are not positioned in the region of arrays which are here present, so these windows also function as closed windows and the observer looking at the mask **25** (and disregarding the portion of the array **21** extending outside the righthand edge of the mask **25**) has an opportunity to view a total of 5 color indicia, *j*, *q*, *u*, *w* and *z* in the absence of all of the remaining color indicia in order to ascertain whether or not a harmonious color system has been selected in this position. Movement of the mask **25** in alignment with any one of its edges, such as the edge **25a** (parallel to the indicia row *p*, *o*, *l*, *n*, *g*, *r*, *t*) will result in the exposure of another set of colored indicia. Because of the arrangement whereby the windows on the mask **25** are aligned in the same relationship in which the indicia on the arrays are aligned, each time a given window is centered upon a given color particle, the other color particles which are to be exposed will also be centered in the respective windows and a clear uniform view of each of the color particles to be exposed in a particular position is thus made possible. Further, because of the alignment of the color indicia (and the windows) in at least two sets of parallel rows, and preferably three sets of parallel rows, it is possible to move the mask **25** in a great plurality of different directions without causing disalignment between the mask **25** and the rows of color indicia.

Each time any mask edge, or row of mask windows, is parallel to any given row of color indicia, as mask edge **25a** parallel to color row *w*, *l*, as shown in Fig. 1, the mask may be moved step by step, placing each window successively over each color indicium. Further, each time any mask edge is parallel to any given row of color indicia, as mask edge **25a** parallel to color row *w*, *l*, as in Fig. 1, the mask may be moved step by step, placing each window successively over the same color indicium, as over color *w*, displacing many different color combinations, in each one of which the same color, as *w*, will appear, thus permitting the user to build many different color schemes around an item of a predetermined color.

It will further be noted that whereas the mask as positioned in Fig. 1 displays five color indicia in the color schemes presented, it can display a different number at other times. For example, the mask, while still retaining its alignment at window row **32**, **33**, with the indicia

row p, q, l, n, q, r , can be moved one step upwardly to the right so that window 32 is centered over indicium r in the neutral scale. The mask will then expose six color indicia instead of five, the selecting windows this time being windows, 32, 29, 35, 36, 30 and 27. Window 28 has this time moved outside of color array 16 thus falling over a blank area, while window 29 has moved over color h in array 16, and window 35 has moved over the indicium which is located just below indicium q in the neutral scale array 26.

It will be noted also that the first scheme, as shown in Fig. 1, having five colors and involving mask windows 32, 30, 36, 27 and 28, presented a color pattern in which the maximum distance between any selecting windows in the same row, windows 28 and 32, was 4X, whereas the second scheme of six colors, involving mask windows 32, 29, 35, 36, 30 and 27, presented a color pattern in which the maximum distance between any selecting windows in the same row, as windows 29 and 32, was 2X. In this way my mask can pick color indicia which are sometimes far apart and which are at other times close together. It can be seen that when the color arrays have an organized arrangement for the color indicia, with the indicia in a given row becoming progressively lighter, or darker, or more vivid, or more grayed, the selecting by the mask of color indicia which are far apart can present greater degrees of contrast in dark and light or in vividness and dullness than would be exhibited when the selected color indicia were close together. For example, when twin windows 38 and 39 appear as selectors the color indicia would show only one step of contrast as compared with four steps of contrast between windows 28 and 32.

One of the unique features of this mask is that any given window, as window 32, may join, at one time, with one group of windows, as with 28, 27, 30 and 36 to pick one scheme, and that this same window, as 32 may join, at another time, with another group of windows, as with 29, 35, 27, 30 and 36, to pick another scheme.

It will also be noted that the general pattern of windows called for in the mask 25 is that wherein the windows in any one row of windows, such as the rows 27, 28, 35, 37, 30, 34; and 38, 39, 40 are spaced an integer multiple of x , and preferably the integer multiple is 2 or 3. It will be appreciated that if the integer is only one, throughout the mask, the mask would show substantially all of the color indicia on the arrays below. Instead, it has been found to be preferable to employ distances of at least $2x$ between the windows and preferably not more than $4x$. This makes possible the maximum number of color combinations without necessitating the presentation to the observer of a great number of color indicia which are only one shade apart (in other words, which are positioned side by side on array. On the other hand, it has been found to be particularly important from a color selection point of view to provide a mask wherein at least one and perhaps two groups of windows, such as the windows 38 and 39 are spaced the distance x . In certain color harmony selections, it has been found to be desirable to employ colors which are only one shade apart, and in such harmony selections, the arrangement of the windows 38 and 39 is particularly useful. In addition, the cooperation between the mask 25 and the array arrangement shown in Figures 1 and 2 is uniquely adapted for the use of a mask having adjacent windows 38, 39, because the arrays, such as the arrays 16 and 17 are positioned with a space therebetween (between the parallel edges 16a and 17a) so that it will be possible to position one of the windows 38 or 39 over a color particle (for example, by inverting the mask 25 as here shown and positioning one of the windows 38 or 39 over the color particle a) so that only one of the adjacent windows 38 and 39 is over a color particle and the other is over a blank area. In this way, maximum

advantage may be taken of the adjacent windows 38 and 39 so that they may be selectively employed to show colors which are one shade apart and yet the mask 25 is not limited to the necessity of showing colors which are only one shade apart in every position thereof.

The mask shape which is shown in Fig. 1 is a six-sided figure. However, it can assume other shapes. It may have more or less windows than shown, and these windows may be in other arrangements than those in Fig. 1, as long as the window placements follow the above principles and are positioned in reference to the predetermined unit of distance used for locating centers of the indicia on the arrays. In masks of other shapes, the mask edges need not be used as positioning agents since the user may position the mask over the arrays just as easily by having any row of mask windows parallel to a row of color indicia on the arrays beneath the mask.

As hereinbefore mentioned, it is most preferable to arrange the color indicia so that they fall in or are alignable with at least three sets of parallel lines. In order to accomplish this, it is necessary to so position the color indicia on any one array. If the color indicia on a given array are positioned, the additional arrays 20 may be suitable aligned so as to obtain a color pattern for the entire combination of arrays. Referring now specifically to the array 41 shown in Figure 5, which contains a color indicia arrangement that is most preferred for use in the instant invention, it will be seen that the color array 41 has a generally triangular shape, substantially that of an equilateral triangle, and the color arrays thereon are arranged in the general shape of an equilateral triangle. The color indicia indicated in Figure 5 are shown as circles instead of hexagons as a simplification, but it will be appreciated that still other shapes may be employed if desired.

As shown in the array 41 of Figure 5, the color indicia are alignable in a first set of parallel lines a_1, a_2, a_3 , and a_4 which are parallel to the edge 41a; a second set of parallel lines b_1, b_2, b_3 and b_4 which are parallel to the edge 41b and a third set of parallel lines c_1, c_2, c_3 and c_4 which are parallel to the remaining edge. These sets of parallel lines are thus arranged so that one of each of the sets will be parallel to a side of the equilateral triangle arrangement here employed. In each of the lines (such as the line a_1) the color indicia are spaced apart the distance x and in each of the sets of lines parallel to the sides 41a, 41b and 41c, the lines (such as the lines a_1 and a_2) are spaced apart the distance

50

$$\frac{x\sqrt{3}}{2}$$

It will also be noted that the color indicia in the array 41 are alignable in still a fourth, fifth and sixth set of parallel lines, one set being indicated at d_1 and d_2 , each of the sets of parallel lines in the fourth, fifth and sixth sets being perpendicular to a side of the array 41. It will also be noted, that in the set d_1 and d_2 the lines d_1 and d_2 are spaced apart the distance x whereas the color indicia, for example in the line d_2 are spaced apart the distance between the parallel lines b_1 and b_3 , which is $x\sqrt{3}$. The arrangement of the fourth, fifth and sixth sets of parallel lines will be apparent without further description, although it will be appreciated that using an array having a greater number of color indicia, such as one having five or six color indicia along each side, will permit a more extensive showing of the fourth, fifth and sixth sets of parallel lines.

It will also be noted that the shortest distance between an array edge, such as the array edge 41a and the color indicia in the row a_1 which are aligned parallel to the edge 41a and are immediately adjacent thereto is

75

$$\frac{x\sqrt{3}}{4}$$

but the distance from the edge 41c to the color particle in the row a_1 immediately adjacent the edge 41c, which distance is measured along the line a_1 , is $\frac{1}{2}x$ or $x/2$. It will thus be seen that the preferred color array 41 has at least one straight edge (and preferably three straight edges) having a plurality of color indicia fixed to the array 41 suitably aligned in a set of parallel rows wherein this set of parallel rows is aligned to intersect an edge (in the manner in which the parallel rows a_1 , a_2 , a_3 and a_4 intersect the edge 41c) with the color indicia in each of the rows immediately adjacent this edge 41c (which would be the color indicia in the row c_4) being spaced from the edge 41c one-half of the predetermined unit of distance x . The reason for this arrangement is that a second array may be suitably disposed in uniplanar relationship with respect to the array 41 so that the edge of the second array (having the same design and arrangement as the array 41) may be disposed in abutting relationship to the edge 41c and the color indicia on either side of the edge 41c will thus be spaced apart the distance x . This arrangement is shown in Figure 4, which will be discussed in detail hereinafter. At least it is necessary that two mating arrays must be fabricated so that the color indicia thereon which are to be positioned on opposite sides of mating edges of these two arrays in a given row of color indicia will be spaced from the edges a total distance of x . In other words, the color particle in one array could be spaced from a given edge thereof a distance of $\frac{1}{4}x$ and the color particle in the mating array would have to be spaced a distance $\frac{3}{4}x$ from the edge thereof which is to cooperate with the edge of the first array. It will be appreciated that the problem is greatly simplified if the color particles in each case are spaced the distance $\frac{1}{2}x$ from one or more edges so that a great benefit in interchangeability may be obtained.

Another feature of the array 41 which has been found to be important is that of providing flattened edges at the apex of the triangle.

The particular arrangement of the flattened or blunted apex of the triangle is best indicated in connection with the array 42 of Figure 3. As shown in Figure 3, the apex of the array 42 is blunted at the edge 42d. This is done in the case of each apex of the equilaterated triangle in order to permit the individual array 42 to be placed in abutting relationship with another array instead of overlapping relationship in order to obtain a given positional relationship. The edge 42d is cut so as to provide an edge which is

$$\frac{x\sqrt{3}}{4}$$

from the center of the nearest color particle 43 (just as the edges 42a and 42c are spaced from the color particle 43 measuring by the shortest distance); but measuring along the row a_1 , or along the row c_4 , it will be noted that the center of the color particle 43 is spaced a distance $x/2$ from the intersecting edges 42c and 42d and the intersecting edges 42a and 42d, respectively.

Referring now to the array arrangement of Figure 3, it will be seen that the arrays 42, 44 and 45 are arranged in substantially uniplanar relationship, with the array 44 overlying a small portion of the array 42 and the array 45 overlying a portion of the array 44. It will be noted, however, that the color indicia on the various arrays here shown are aligned in at least 2 and in this case 3 sets of parallel lines, one set being indicated by the heavy lines 46, 47; another set being indicated by the heavy lines 48, 49 and a third set being indicated by the heavy lines 50, 51, 52.

It will also be noted in Figure 3 that a neutral scale array 52 is positioned in overlying relationship with respect to the color array 45 and the color indicia in the neutral scale array 52 are positioned so that those color indicia 52a, 52b and 52c in the portion of the neutral scale 52 which overlies the color array 45 are positioned

directly above the color indicia in the array 45 which should normally be exposed and are thereby positioned in the proper alignment for the sets of parallel rows.

Referring to Figure 8, it will be seen that the neutral scale 52 comprises an elongated array backing with a row of color indicia 52a, 52b, 52c, 52d and 52e aligned thereon so as to be spaced apart the distance x . The distances from each of the color indicia to the edges of the neutral array 52 are the same as those distances hereinbefore indicated in connection with the color indicia immediately adjacent a side of a triangular array such as the array 42.

Referring now to Figure 4, it will be seen that the arrays 53, 54 and 55 shown therein are uniplanarly disposed with an edge of each array abutting an edge of another of the arrays. Thus, the edge 53a of the array 53 abuts the edge 54a of the array 54. The edge 54b of the array 54 abuts the edge 55a of the array 55. In each case, it will be noted that the arrays 53, 54 and 55 are so positioned with the color indicia thereon that the color indicia fall in three sets of parallel lines, which in each case are also parallel to one side of each of the arrays 53, 54 and 55. Thus, the parallel lines in the set associated with the line 56 are also parallel with the array edges 53a, 54a and 55b. The other two sets of parallel lines are indicated generally by the heavy line 57 and the heavy line 58.

Assuming the color array 53 is made up for the color red, the color particle 59 at one apex of the array 53 will be pure red and the color particle 60 at another apex of the array 53 will be a light tint of red and the color particle 61 at the third vertex will be a relatively dark shade of red. The color particles in between the particles 59, 60 and 61 at the vertices of the array will vary between the strength of the colors represented at the vertices. Thus, the color particles 62 and 63 will be increasingly lighter tints of red, with the particle 60 being the lightest tint of red, etc. The arrangement of the color particles is described in detail in said application Serial No. 235,327 and need not be further discussed herein. However, it will be noted that the same position shown in Figure 4 for the array 53 may be obtained using three different color indicia arrangements. In other words, the array 53 may be turned around so that the dark red color particle 61 is in the position shown for the pure red color particle 59, etc. This gives a total of three positions for each color array 53, 54 or 55 in the arrangement shown in Figure 4, and thus a total of nine different possible color combinations or nine times the possible total number of color combinations obtainable using this arrangement.

Referring now to Figure 5, it will be seen that a total of three arrays 41, 64 and 65 are used plus the neutral scale 52 hereinbefore shown. The arrangement between the arrays 64 and 65 shows the advantage of having the blunted apex edge 65a at the apex or vertex of each of the triangularly shaped arrays 64, 65. The heavy lines indicated in Figure 5 show the alignments of the various parallel rows of color indicia. Also, the arrow at 66 indicates possible movement of the color array 41 through a series of positions. Thus, the color array 41 may be moved toward the array 65 or away from the array 65 along a line aligned with the arrow 66 so as to produce a new color pattern each time the array 41 is moved the distance x along the line indicated by the arrow 66.

Figure 6 shows still another arrangement which may be used for the triangularly shaped color arrays 67, 68 and 69 shown therein. Again, the heavy lines indicate the direction in which the sets of parallel rows extend. Here again, the blunted vertices at 69a and 68a prevent overlapping of the arrays 68 and 69 in the position shown.

Figure 9 shows a single array 70 having 4 instead of 3 sides and having the general shape of a square. The indicia are positioned thereon at 71, 72, etc. in the form

of squares and the alignment of the arrays thereon is such that 3 sets of parallel rows of indicia are indicated by the heavy lines 73, 74 and 75. The color indicia in the rows 73 and 74 are each spaced apart the same distance. A neutral array 76 is also shown in conjunction with the array 70. It will be noted that the neutral scale or array 76 has cutaway portions along the left-hand edge 76 thereof so as to permit the neutral array 76 to overlap partially one side of the color array 70 without covering any of the color indicia thereon. The neutral scale color indicia 77, 78, etc. are arranged in a row, as indicated, and spaced from each other in that row the same distance which the color indicia are spaced from each other in the row indicated by the heavy line 75 on the array 70, so that perfect alignment may be obtained between the neutral scale color indicia 77, 78, etc. and the color array indicia 71, 72, etc.

Referring now to Figure 10, it will be seen that the arrangement there shown comprises a total of four arrays 79, 80, 81 and 82. In Figure 10, the showing is primarily diagrammatical in that the centers of the color indicia are indicated, for example, at 83 and 84 in the array 80, shown with connecting lines which indicate the direction of the sets of parallel rows. The color indicia used may be in the form of squares 85 and 86 as indicated in one corner of the array 79, or the color indicia may be in the form of circles or some other similar shape. The arrays shown in Figure 10 are rectangular in shape, but the arrangement of the color indicia thereon as indicated permits these arrays to be positioned in abutting relationship along the full length of their edges, as in the case of the arrays 79 and 82; or in partial abutting relationship along their edges as in the case of the arrays 79 and 80 and the arrays 80 and 82, and the arrays 80 and 81; or the arrays may be positioned in overlapping relationship, as in the case of the arrays 81 and 82. In each case, the alignment of the color indicia throughout the assembly is in the sets of intersecting parallel rows hereinbefore described in detail.

Referring now to Figure 11, it will be noted that the arrays therein are again all of the same shape. The arrays 87 and 88 have the general shape of a rhombus and the array 89 is also in the shape of a rhombus, except that it is positioned differently with respect to the other two so as to fit therebetween. Again, the color indicia indicated at 90, 91, 92, etc. are represented diagrammatically only by their centers, but it will be seen that the arrangement of sets of parallel rows hereinbefore described is again present in the arrangement of Figure 7. Also, it will be noted that two corners (having acute angles) in each rhombus 87, 88 and 89 have been blunted in the manner in which the vertices of the triangles are blunted, for example, in connection with the array 42 of Figure 3, so as to serve the same function, which is indicated best in the arrangement of Figure 5 between the arrays 64 and 65.

Referring now to Figure 12, it will be seen that still another arrangement may be obtained using a plurality of arrays 93, 94 and 95, each of which has the general shape of a rhombus and which has color indicia thereon 96, 97, 98, etc. arranged in the same manner in which the color indicia 90, 91, 92, etc. are arranged in the case of each of the arrays 87, 88 and 89. In this case, the arrays 93, 94 and 95 are arranged in abutting relationship, so as to obtain the desired alignment in parallel rows and sets of rows for the color indicia mounted thereon. It will also be noted that the arrangement of Figure 12 permits additional flexibility in that still another color array may be mounted at the position indicated in dotted lines at 99.

In the case of individual color arrays, such as those shown in Figures 9, 10, 11 and 12, which do not have color indicia positions thereon solely in the shape of a triangle, it will be appreciated that the color indicia positioned thereon may have a number of shade and tint

5

relationships. The color indicia may be positioned thereon in the form of a pair of triangles each of which contains different shades of the same color or of a different color, other arrangements may also be used, as those skilled in the art will appreciate.

Referring now to Figure 13, it will be seen that the color arrays 100, 101, 102 and 103 each have the shape of a segment of a circle. In each of these arrays 100, 101, 102 and 103, the color indicia located thereon are indicated only by their centers, as at 104, 105, etc., so that it can be seen that the color indicia are aligned in three sets of parallel rows of indicia. It will be noted that the segments have two straight edges and one curved edge, and it is preferable in the case of the instant color arrays to have at least one straight edge which may be positioned in abutting relationship with a straight edge of another array and for best operation and interchangeability there should be two and most preferably three straight edges. However, there is a particular advantage in the use of the segment arrangement shown in Figure 13 in that the arrays might be mounted, for example, in groups of four to six so as to form a complete circle, as shown in Figure 16. And the arrays thus mounted to form a circle such as the circle 106 in Figure 16 may be affixed to a permanent mounting board adapted for rotation about the center, so that the movement of the arrays from one position to another may be very easily handled.

Referring again to Figure 13, it will be noted that the color indicia 104, 105, etc. are positioned on each of the arrays, such as the array 101 in the generally triangular shape hereinbefore described in detail, for example, in connection with the array 41, this greatly facilitates the alignment of one segment 100 with another segment 101 so as to complete the sets of parallel rows of color indicia throughout the pattern, without necessarily positioning the segments in the same relationship in which they would appear in a circle, such as is done in connection with the segments 102 and 103.

Another feature of Figure 13 resides in the additional circular color array 107, which may be mounted for rotation in order to facilitate rearrangement of the color indicia. In such instance, the color indicia mounted on the array 107 (which may also be a neutral array) are so spaced from each other that they have the same pattern as that on the segment arrays 100, 101, etc. The arrangement on the basis of centers is shown by virtue of the light lines connecting the centers in Figure 13, and it will be noted that the color indicia 109, 110, etc. on the array 107 are suitably aligned and spaced from each other to fall into alignment with the parallel rows of indicia shown on the segment arrays 100, 101, etc.

In Figure 16, a mounting board 111 is shown which has a plurality of circular color arrays 106, 112, 113 and 114 mounted thereon. As is indicated in Figure 17, the board is provided with a pedestal member 115 having a central peg 116 which fits through a suitable aperture in the array 113 so as to rotatably mount the array 113. Similar arrangement is provided for the other arrays 106, 112, and 114. Also, a similar arrangement with a slightly higher pedestal 117 is provided for the centrally positioned neutral scale 118. Using the arrangement shown in Figures 16 and 17, it will be appreciated that each circular array 106 may be made up of a plurality of segmental arrays such as the arrays 102 and 103 of Figure 13, so that alignment between the color indicia (not shown) on all of the arrays as well as the neutral scale array 118 may be accomplished, merely by rotation of the arrays so as to align the indicia thereon. In each case, the indicia are so positioned in final proper alignment that the indicia on a given array are preferably spaced apart the predetermined unit of distance x and the indicia lying in a given row extending from one color array to another are positioned an integral multiple from each other along the row.

75

Figure 14 shows still another shape of array. In this case, the arrays 119, 120, 121 and 122 have a zig-zag edge on one side, as at 119a and 121a and a straight edge on the other side, as at 121b and 119b. This permits the positioning of the arrays in back-to-back relationship as shown in connection with the arrays 119 and 120, and in a face-to-face relationship as shown in connection with the arrays 121 and 122. Also, the zig-zag edges are so designed as to permit interlocking relationship between the arrays on such basis, if such is desired. It will be noted again that the color indicia, shown only by their centers at 123, 124, etc. are again aligned as hereinbefore indicated in the sets of parallel rows, so as to permit alignment of color indicia across a plurality of arrays.

Still another array arrangement is shown in Figure 15. In Figure 15, the arrays 125 and 126 are shown as octagons, although it will be appreciated that other polygon shapes may be used. Here again, it will be noted that there are continuing parallel rows of color indicia extending across from the array 125 to the array 126, the color indicia again being indicated only by their centers as at 127, 128, etc. Here the arrays 125 and 126 are shown in abutting relationship.

It will be understood that modifications and variations may be effected without departing from the scope of the novel concepts of the present invention.

I claim as my invention:

1. A color harmony selection system comprising a pair of color arrays disposed with an edge of one array parallel to an edge of the other array, each of said arrays having individual color indicia affixed thereto, the indicia on both arrays being aligned in a first set of parallel rows, a second set of parallel rows intersecting the first set at the centers of the indicia and a third set of parallel rows intersecting the first and the second sets at the centers of the indicia, the indicia in each row of said sets of rows being spaced an integer multiple of a predetermined unit of distance from any indicia in that row immediately adjacent thereto; and a mask separate and apart from said arrays and movable with respect thereto superimposed upon said arrays, said mask having indicia-sized windows therein which are aligned in said sets of parallel rows and are spaced from each other in each of such rows an integer multiple of said predetermined unit of distance, whereby positioning of the mask to expose one of said indicia at one window results in exposure of other indicia in other windows.

2. A color harmony selection system comprising a pair of color arrays disposed with an edge of one array parallel to an edge of the other array, each of said arrays having individual color indicia affixed thereto, the indicia on both arrays being aligned in a first set of parallel rows and a second set of parallel rows intersecting the first set at the centers of the indicia, the indicia in each row of said sets of rows being spaced an integer multiple of a predetermined unit of distance from any indicia in that row immediately adjacent thereto, and a mask separate and apart from said arrays and movable

with respect thereto superimposed upon said arrays, said mask having indicia-sized windows therein which fall in two sets of intersecting parallel lines that are alignable with said first and second sets of rows, and a pair of such windows being positioned in one of said parallel lines and spaced apart said predetermined unit of distance with the each of remaining windows positioned in any given parallel line being spaced apart from each of the other windows more than one integral multiple of said predetermined unit of distance, whereby positioning of the mask to expose one of said indicia at one window results in exposure of other indicia in other windows coupled with the exposure of two immediately adjacent indicia at said pair of windows.

3. In a color harmony selection system, a color array comprising a flat mounting member having edges in the shape of an equilateral triangle and having a plurality of color indicia detachably secured thereto, said indicia being arranged in the form of an equilateral triangle with an indicium containing a selected pure color at one vertex of the triangle, an indicium containing a light tint of the same color at another vertex and an indicium representing a dark shade of the same color at the third vertex of the triangle, and indicia disposed between the vertices, the indicia disposed between the vertices varying progressively in shades of the selected color between the two vertices, the indicia on said array being aligned in three sets of parallel rows each intersecting the other two sets at the centers of the indicia, at least two of said sets being aligned to intersect each edge, and the indicia in each row being spaced from each other a predetermined unit of distance with the indicia in each row immediately adjacent one of said edges being spaced one-half said predetermined unit of distance therefrom measured in the direction of the row intersecting the edge, said color array being adapted for use with a mask separate and apart from said array and movable with respect thereto while superimposed upon said array, said mask having indicia-sized windows therein which are aligned with said sets of parallel rows and are spaced from each other in each of such rows an integer multiple of said predetermined unit of distance, whereby positioning of the mask to expose one of said indicia at one window results in exposure of other indicia in other windows.
